UNITED STATES PATENT OFFICE

JOHN J. CATRON, OF BONHAM, TEXAS

AGITATION MEANS AND METHOD FOR ICE MAKING

Application filed April 26, 1930. Serial No. 447,719.

This invention relates to new and useful improvements in agitation means and methods for ice making.

One object of the invention is to provide a method for thoroughly agitating water in an ice can so as to remove the impurities and air bubbles therein, whereby clear, colorless and wholesome ice is produced.

A further object of the invention is to provide means for introducing diverging jets of water under pressure into the bottom of the ice can whereby the water contained therein will be thoroughly agitated.

Another object of the invention is to provide means for introducing compressed air into the bottom of the ice can whereby the air will serve to agitate the water at opposite sides of said can.

A still further object of the invention is to provide means for alternately discharging water and air from a tubular conductor at the bottom of the column of water in an ice can, whereby the column of water is completely agitated.

25 A construction designed to carry out the invention will be hereinafter described together with other features of the invention.

The invention will be more readily understood from a reading of the following specification and by reference to the accompanying drawing in which an example of the invention is shown, and wherein:

Figure 1 is a view partly in elevation and partly in section of a device constructed in accordance with the invention,

Figure 2 is a vertical sectional view taken on line 2—2 of Figure 1,

Figures 3 and 4 are detailed views of the hanger construction,

Figures 5 and 6 are details of the tube nozzle and

Figure 7 is a detail of the control valve.

In the drawing the numeral 10 designates an ice can of usual construction. A hanger 11 is mounted in the upper end at one side of the can by a bracket 12 engaging over the edge of said can and secured by a screw 13.

50 The hanger includes a tubular shank 14 which extends from the bracket 12 and is provided at its outer end with radial slots

15. A cylindrical rocker 16, having a connecting pipe 17 extending therethrough, is mounted within the tubular shank with the opposite ends of the pipe 17 protruded through the slots 15. An elongated tube 18 is screw threaded onto the lower end of the pipe 17 and depends into the can. The opposite and lower end of the tube 18 is tapered and provided with a nozzle 19 suitably secured to the tube. The nozzle has an arcuate end provided with a plurality of radial or diverging ports 20. These ports connect with the bore of the tube 18 so that any fluid contained in the tube may be expelled therefrom in diverging directions.

The upper end of the pipe 17 is connected by a union 21 to a flexible tubular conductor 22. The opposite end of this conductor is connected by a union 23 to an outlet port 24 of an intermittent flow valve 25. This valve has an inlet port 26 which is connected by a conductor 27 to an air compressor (not shown) for supplying compressed air to said valve. The valve also has an exhaust port 28. The valve is of the rotating barrel type, with the barrel thereof rotated in any suitable manner. The valve is constructed so that as the barrel 29 rotates, the outlet port 24 and the intake port 26 will be intermittently connected, thus intermittently supplying compressed air through the conductor 22 to the tube 18. Also the rotation of the barrel will intermittently connect the port 24 and the exhaust port 28, thus allowing the air within the conductor 22, pipe 17 and tube 18 to escape through the valve and the port 28.

When the ports 24 and 28 are connected the water will enter the tube 18 through the ports 20 in the nozzle and thereby force out any air which may be within the tube. When the ports 24 and 26 are connected, the compressed air from the conductor 27 will enter the conductor 22 and tube 18, thereby forcing out the water within the tube through the ports 22 in diverging jets. As the ports 20 are smaller than the central bore of the tube 18 the water will be expelled through said ports under increased velocity and penetrate the water below the nozzle to all the corners at the bottom of the can, thereby thoroughly

agitating the bottom portion of said water. As the compressed air follows the water and discharges from the tube, said tube will tend to rise through its buoyance toward a horizontal position, and as the tube is pivoted at its upper end, it will swing in an arc to one side of the can. The air discharging from the nozzle 18 will rise upwardly through the water aerating the same and thereby furthering the agitation of the water.

As the valve barrel 29 rotates and the ports 24 and 28 of said valve are connected, water will rise within the tube to the level of the water in the can and expel the air in said tube through the exhaust port 28 thereby causing the tube through its own weight to resume a vertical position. It will be noted that the swinging action of the tube, due to its buoyancy, may take place in either direction toward opposite sides of the can.

As the valve 29 rotates and connects the ports 26 and 24, the compressed air entering the tube 18 will expel the water from the tube as hereinbefore explained. It will be noted that the jets of water being expelled from the nozzle will thoroughly penetrate the water in the can as the jets have sufficient velocity to displace the water in said can. By this action the water in the lower portion of the can is thoroughly agitated. The swinging of the tube through its buoyancy will distribute the compressed air to opposite sides of the can, which air on rising in the water will thoroughly agitate the upper portion of said water. Obviously the water contained in the can is completely and thoroughly agitated.

Various changes in the size and shape of the different parts, as well as modifications and alterations, may be made within the scope of the appended claims.

What I claim, is:

1. The method of agitating water in the art of ice making which consists, in storing water in an upright container, then agitating the lower portion of the body of water by ejecting jets of water thereinto, alternately agitating the entire body of water by ejecting jets of air thereinto at the bottom of said body of water, and changing said point of air injection from the point of water injection in the bottom of said body of water to transversely aerate the entire body of water.

2. The method of agitating water in the art of ice making which consists, in storing water in an upright container, then agitating the lower portion of the body of water by ejecting water in a plurality of jets downwardly thereinto, alternately agitating the entire body of water by ejecting downwardly at the bottom of said body of water spaced jets of air whereby the body of water is transversely aerated.

3. In an ice making device, the combination with an upright water container, of a fluid

conductor, means for pivotally supporting the conductor in the container with its lower end adjacent the bottom of said container, said conductor being free to swing from side to side of the container, and a nozzle at the bottom of the conductor having a plurality of downwardly directed ports.

In testimony whereof I affix my signature.

JOHN J. CATRON.
